COCKTAIL TABLE OR THE LIKE

Joseph E. Adkinson, 3807 Leland St.,
Chevy Chase, Md. 20015

Filed Apr. 23, 1974, Ser. No. 463,291

Term of patent 7 years

Int. Cl. D6—03

U.S. Cl. D6—177

FIG. 1 is a perspective view of the cocktail table showing my design;

FIG. 2 is a top plan view showing the cocktail table of FIG. 1; and

FIG. 3 is a side elevational view of the cocktail table of FIGS. 1 and 2.

I claim:

The ornamental design for a cocktail table or the like, substantially as shown.
